Attorneys

UNITED STATES PATENT OFFICE.

JOSEPH A. BOEHRINGER, OF BUFFALO, NEW YORK.

BANJO PIANO.

Application filed March 9, 1922. Serial No. 542,473.

To all whom it may concern:

Be it known that I, JOSEPH A. BOEHRINGER, a citizen of the United States, residing in Buffalo, in the county of Erie and State of New York, have invented new and useful Improvements in Banjo Pianos, of which the following is a specification.

This invention relates to a musical instrument and more particularly to a stringed instrument including a key-operated mechanism for picking the strings to simulate a banjo, guitar, mandolin, or similar instrument.

One object of the invention is to provide a simple and effective picker mechanism which is reliable in operation and composed of few parts which are not liable to get out of order.

A further object is to provide the instrument with simple means for producing a close imitation of the banjo tone.

In the accompanying drawings:

Figure 1 is a front view of a musical instrument embodying my invention, with the casing partly broken away. Figure 2 is a transverse vertical section on line 2—2, Fig. 1. Figures 3 and 4 are enlarged sectional elevations of the picker mechanism showing different positions thereof. Figure 5 is a fragmentary perspective view of one of the bridge supports. Figure 6 is a sectional elevation of a modified form of the improvement.

Similar characters of reference refer to like parts throughout the several views.

For the purpose of illustrating the invention, a comparatively small instrument of three octaves is shown in the drawings, but it will be understood that the improvement is equally applicable to large instruments of the size of ordinary pianos.

10 indicates the case of the instrument which may be rectangular and which is provided with a sounding board or box 11 constructed to imitate a banjo or similar stringed instrument. This sounding board is secured in an upright position in the lower rear portion of the case. The strings 12 of the instrument are supported near their ends on suitable bridges, one of which is shown at 13. Each bridge is preferably supported upon a number of spaced rods 11^a preferably of steel which are partly seated in grooves 11^b in the face of the sound board or otherwise mounted thereon, substantially parallel with said face. Interposed be-

tween these raised rods and the base of the bridge is a strip 13^a of rawhide, such as buckskin, or equivalent material, for the purpose of imitating the characteristic sound of the banjo.

The keys 14 of the instrument are arranged in the upper front portion of the case and fulcrumed near their rear ends upon a longitudinal pivot rod 15 suitably supported in this case.

Co-operating with each string of the instrument and actuated by the corresponding piano key is the picker mechanism which is preferably constructed as follows:

16 represents upright rock bars or picker levers, each of which is disposed between one of the keys 14 and the corresponding string 12, being spaced a suitable distance from the latter, as shown in Fig. 2. Each picker lever is capable of a compound reciprocating and oscillating movement relatively to the respective string and the same is suspended from the upper rear wall of the case through the medium of a yielding connection, preferably in the form of a coil spring 17. The latter normally tends to hold said picker lever in its elevated or inoperative position shown by full lines in Figs. 1, 2 and 3. At a short distance below its upper end, the picker lever is provided with a rearwardly extending fulcrum stud 18 which is guided for sliding movement in an upright groove or way 19 formed in the rear wall of the case, while the lower end of said lever terminates in a forwardly projecting finger or elbow extension 20 which is guided in a slot or comb 21 formed in the base of the case. This finger is operatively connected to the companion piano key, so that when the latter is depressed, the corresponding picker lever descends with it and its lower arm is rocked toward the string. For this purpose a push rod 22 extends from the underside of the key to the upper side of the companion finger 20, the ends of the rod being seated in notches or depressions 23 formed in said parts, as shown in Fig. 3. The bearing edge 24 of the fulcrum stud is round or semi-circular in form to permit the picker lever to rock freely about a horizontal axis. Said lever carries a suitable picker or picker pin 25 adapted to trip over the corresponding string of the instrument for sounding the same when the lever is depressed through the manual action of the corresponding key.

- Each of the springs 17 is preferably disposed at a forwardly inclined angle, as shown in Figs. 2, 3 and 4, for the purpose of exerting a rearward as well as an upward 5 pull on the picker lever 16 and thus tend to swing its lower arm away from the companion string on its upward stroke, to cause its picker to clear the string. In order to render this clearing action positive upon 10 10 releasing the depressed piano key and prevent picking of the string on the upward stroke of the picker lever, the lower end of the latter is preferably provided on its rear side with a flat return spring 26 which bears 15 15 against a projection 27 extending forwardly from a fixed rail 27^a or other suitable support. This spring constantly tends to rock the lower arm of the picker lever forwardly about its slidable fulcrum 18, withdrawing 20 20 the picker clear of the corresponding string before the upper string 17 elevates said lever and its actuating key to normal position, in which the picker is located above and slightly forward of said string, as best 25 25 shown in Fig. 3.

The downward stroke of each picker lever is limited by a buffer or cushion 28 secured to the lower front end of the finger 20 and contacting with the bottom of the case 10, 30 30 while its upward stroke of said lever is limited by the fulcrum stud 18 abutting against a shoulder 29 formed at the upper end of the guide groove 19. The rocking movement of the picker lever and its actuating key is limited in one direction by the 35 35 spring 26 and projection 27 and in the opposite direction by the front end of the finger 20 striking against the front base rail 30 of the piano case.

40 The operation of the instrument is as follows:

In the normal position of the keys, the picker levers 16 are elevated, as shown by full lines in Figs. 1, 2 and 3, and the pickers 45 45 stand above and forwardly of the respective strings. Upon depressing a key, the corresponding picker lever descends therewith and at the same time rocks on its fulcrum 18, the initial depression of the key 50 50 bringing the picker 25 directly over the corresponding string, ready to pick it, as shown by dotted lines in Fig. 3; while by the final depression of the key the picker is caused to trip over the string and pick it, in an 55 55 obvious manner. Upon releasing the depressed key, the strained springs 17 and 26 react and return the picker lever and the key to their former position. During the initial return movement of this lever, its 60 60 lower arm is swung forwardly by the spring 26 simultaneously with the elevation of the lever by the spring 17, thus positively withdrawing the picker to a position clear of the string, as shown by dotted lines in Fig. 4.

65 The remainder of the upward stroke is in a

substantially vertical line avoiding engagement of the picker with the string.

In Fig. 6 is shown a modified construction of the means for positively deflecting the picker lever away from the string after 70 picking it. Instead of employing a spring for this purpose, as in the previously described construction, the lower end of the picker lever 31 is provided with an inclined deflecting face 32 which is adapted to contact with a roller 33 arranged in the lower portion of the instrument case. In this case, the key 34 may be integrally connected with the picker lever. In the normal inoperative position of the parts, shown by full lines in 80 this figure, the suspension spring 35 holds the picker lever away from the corresponding string with its deflecting face out of contact with the roller 33. Upon depressing the key, its initial movement rocks the picker 85 directly over the same and the lower end of the deflecting face 32 contacts with the roller 33, as shown by dotted lines in Fig. 6. The further downward movement of the key 90 90 first causes the string to be picked and the picker lever then to be deflected forwardly to withdraw the picker from the string. When the key is released, the spring 35 raises it together with the picker lever to 95 its initial position.

I claim as my invention:

1. In an instrument of the character described, the combination of a sound-producing part, and picker mechanism comprising 100 a picker lever capable of a compound reciprocating and oscillating movement relative to said sound producing part, means for effecting said movements of the picker lever, yielding means for suspending the picker lever from a point above its fulcrum and for restraining movement of said lever out of its inoperative position, and means for actuating said lever to pick the sound-producing part.

2. In an instrument of the character described, the combination of a sound-producing part, and picker mechanism comprising a picker lever fulcrumed intermediate its ends for movement toward and from said sound-producing part and capable of reciprocating relatively thereto, means for effecting said movements of the picker lever, means arranged to engage one arm of said lever for actuating it in a direction to engage said part, and means engaging the other arm of said lever for actuating it in a direction to clear said part.

3. In an instrument of the character described, the combination of a sound-producing part, and picker mechanism comprising a longitudinally-movable picker lever having a sliding fulcrum intermediate its ends and capable of swinging toward and from said sound-producing part, means for ef- 125 130

fecting said movements of the picker lever, yielding suspension means attached to one arm of said picker-lever and tending to move it to inoperative position, and means 5 arranged to engage the other arm of said lever for depressing it to pick the sound-producing part.

4. In an instrument of the character described, the combination of a sound-producing part, and picker mechanism comprising a yieldingly-suspended picker-lever having a sliding fulcrum and capable of a compound reciprocating and oscillating movement relative to said sound-producing part, 10 means for effecting said movements of the picker lever, and means for actuating said lever.

5. In an instrument of the character described, the combination of a sound-producing part, a yieldingly-suspended picker lever having a sliding fulcrum and capable of compound reciprocating and oscillating movement relative to said part and normally spaced therefrom, means for effecting said 20 movements of the picker lever, means for depressing said lever to pick the sound-producing part, and means for withdrawing said lever from said part after the same has been picked.

30 6. In an instrument of the character described, the combination of a sound-producing part, and picker mechanism including a longitudinally-movable picker lever fulcrumed for movement toward and from said sound-producing part, a spring for suspending the picker lever from a point above its fulcrum and tending to swing said lever away from the sound-producing part, and means for actuating said lever to pick the 35 sound-producing part.

7. In an instrument of the character described, the combination of a sound-producing part, a longitudinally-movable lever fulcrumed intermediate its ends above said 40 sound-producing part, the lower arm of said

lever carrying a picker arranged to co-operate with said part, a suspension spring connected to the upper arm of said lever and arranged at an angle thereto to swing the lower arm of the lever away from the sound-producing part, and means for depressing said lever to pick said part. 50

8. In an instrument of the character described, the combination of a sound-producing part, a longitudinally-movable lever fulcrumed intermediate its ends above said sound-producing part, the lower arm of said lever carrying a picker arranged to co-operate with said part, a suspension spring connected to the upper arm of said lever and tending to swing its lower arm away from the sound-producing part, means for guiding said lever in its longitudinal movements, and an actuating member for depressing said lever. 55 60

9. In an instrument of the character described, the combination of a sound-producing part, a picker lever capable of a compound longitudinal and rocking movement relative to said sound-producing part, said lever having an angular extension on the side away from the sound-producing part, and an actuating member operatively connected to said lever extension to depress the lever and swing it toward the sound-producing part. 70 75

10. In an instrument of the character described, the combination of a sound-producing part, a picker lever capable of a compound longitudinal and rocking movement relative to said sound-producing part, said lever having an angular extension on the side away from the sound-producing part, an actuating member operatively connected to said lever extension to depress the lever and swing it toward the sound-producing part, and a suspension spring for said lever arranged to swing it away from the sound-producing part. 80 85
